[57] CLAIM

The ornamental design for a microphone housing, as shown and described.

DESCRIPTION

FIG. 1 is a prospective view of a microphone housing according to the invention;

FIG. 2 is a top view of FIG. 1;

FIG. 3 is a side view of FIG. 1, the other side being the same as the side shown;

FIG. 4 is a front view of FIG. 1;

FIG. 5 is a rear view of FIG. 1; and,

FIG. 6 is a bottom view of FIG. 1.

The broken line showing of the wiring protruding out of the microphone housing in FIGS. 4 and 5 is for illustrative purposes only and forms no part of the claimed design.
